UNITED STATES PATENT OFFICE.

GEORGE HENRY PADGETT, OF EDWARDS, NEW YORK.

TAG.

Application filed March 21, 1922. Serial No. 545,476.

To all whom it may concern:

Be it known that I, GEORGE H. PADGETT, a citizen of the United States, and a resident of Edwards, in the county of St. Lawrence 5 and State of New York, have invented a new and Improved Tag, of which the following is a full, clear, and exact description.

This invention relates to improvements in tags, particularly to a tag which is adapted to be removably secured to a phonograph disc record and pass into the hands of the ultimate purchaser with the record, said tag having displayed thereupon certain data and information which will be of interest and 15 value to the purchaser of the record.

A further object is to provide a tag of this character, which can be firmly secured to the record, and yet which can be readily removed for the purpose of demonstrating 20 the record before sale.

A still further object is to provide a tag of this character, which after its removal from the record may be placed in a loose leaf binder, these tags serving as an index 25 to the records to which they were originally attached.

Still another object is to provide a device of the character stated, which will be simple and practical in construction, neat and 30 attractive in appearance, and comparatively inexpensive to manufacture.

With these and other objects in view, the invention consists in certain novel features of construction and combinations and arrangements of parts as will be more fully 35 hereinafter described and pointed out in the claims.

In the accompanying drawings:

Figure 1 is a fragmentary plan view of a 40 record showing my improved tag in attached position;

Figure 2 is a fragmentary edge view of the tag and record, with parts broken away for clearness; and

Figure 3 is a perspective view showing the manner of securing the tags in a loose leaf binder.

Referring in detail to the drawings, I have used the reference numeral 1 to designate a 50 conventional disc record for phonographs, provided with the usual post hole 2 at its center. My improved tag, designated by the reference numeral 3, is provided with a central transverse fold line so that the tag in-

cludes a pair of flaps 4 located upon opposite sides of the record and united at the edge of the record. One of these flaps is provided with an eyelet 5 adapted to register with the central post hole 2 and the other flap carries a paper clip or fastener 6 adapted to be passed through the central opening in the record and bent over upon the opposite flap of the tag.

The eyelet 5 is provided with the view of resisting possible wear upon the tag caused by the bending of the fastener 6 upon the flap 4. I have shown a conventional type of paper fastener, known as the McGill fastener, including a pair of bendable tongues, one of which is passed through the post hole and overlies the opposite flap of the tag, and the other of which, is bent upon the inner face of the flap by which the fastener is carried and lies between this flap and the record, as seen most clearly in Figure 2. 75 It will be obvious, however, that other fastening devices might be substituted for the particular fastener shown.

The tags 3 may have displayed thereon the words of the subject or the score, or 80 both as desired. They may also have any history or description, or advertisement displayed thereupon. For the purpose of aiding musicians or students of music, I prefer to print the words of vocal subjects upon the tags, thus suggesting to the ear a true and correct understanding of the subject, or in the case of instrumental records, to supply the printed score upon the tag which 85 will enable a musician to easily interpret and follow the phonograph with his own instrument.

When the tag has been detached from the record, series of registering perforations 7 in the edges of the flaps 4 facilitate the 95 ready mounting of the tags in a conventional loose leaf binder, such as 8. The perforations 7 are adapted to receive the posts or rings 9 of the binder and the tags when thus bound form a convenient index to a 100 collection of records.

Although I have illustrated the preferred embodiment of the invention, various slight changes and alterations might be made in the general form and arrangement of the 105 parts described, or in the indicia displayed upon the tags without departing from the invention, and hence I do not wish to limit

myself to the precise details set forth, but shall consider myself at liberty to make such slight changes and alterations as fairly fall within the spirit and scope of the appended 5 claims.

I claim:

1. The combination with a disc record, of a tag having two flaps straddling the record 10 the flaps extending beyond the port-hole thereof and provided with openings adjacent their ends registering with each other and with the said port hole, and means passing through the flaps and the post hole of the record and detachably securing the tag 15 to the record, said tag having produced thereon the subject matter of the record, substantially as and for the purpose set forth.

2. As a new article of manufacture, a tag 20 having a pair of flaps adapted to straddle a phonograph disk record, said tag being adapted to have indicia relating to a particular record produced thereon and said flaps having registering openings along one 25 lateral edge of the tag, for the purpose described.

3. A tag of the class described, including 30 a pair of flaps adapted to straddle a disc phonograph record, and means adapted to be passed through the central post hole of a record for detachably connecting the flaps, said means including a bendable device secured to one flap adapted to be passed 35 through the post hole and the other flap and bent over the face of the other flap, said

last mentioned flap including an eyelet receiving said bendable device.

4. The combination with a disc record, of a tag having two flaps straddling the record and provided adjacent their ends with openings 40 registering with each other and with the central post hole of the record, and means for detachably securing the tag to the record, said means consisting of a pair of bendable tongues, one of which lies on 45 the inner face of the flap by which the fastener is carried and the other extends through the post hole of the record and lies on the outer face of the other flap.

5. As a new article of manufacture, a tag 50 having a pair of flaps adapted to straddle a phonograph disk record and to extend inwardly from the peripheral edge of the disk record beyond the post receiving opening in the latter, each of said flaps having in its 55 free end portion an opening adapted to register with the post receiving opening of the record and with the opening in the end portion of the other flap when said flaps are in straddling relation to the record, said 60 openings being adapted to receive a fastening device for releasably securing the tag to the disk record, each of said flaps being adapted to have indicia relating to the work on one face of the disk record produced 65 on the outer face thereof and said flaps having registering openings therethrough adjacent to a lateral edge of the tag, for the purpose described.

GEORGE HENRY PADGETT.
